UNITED STATES PATENT OFFICE

2,532,766

CONVERTIBLE TABLE WITH VERTICALLY
ADJUSTABLE MECHANISM

Paul François Galleret, Le Havre, France

Application November 14, 1947, Serial No. 785,923
In France July 10, 1947

2 Claims. (Cl. 311—35)

1

The present invention has for its object a convertible table which is chiefly characterised by the fact that it may be used, at will, in each of the following three different forms:

(a) As a sideboard or dinner-table for at least two persons,

(b) As a dinner-table for at least four persons, and

(c) As an apartment bar.

This table is in the first place characterised by the fact that it comprises a rectangular board pivotable about a central axis and able to assume two positions: a first position in which it covers two fixed and spaced panels which are symmetrical with respect to the central axis, in which case the table constitutes a sideboard or a rectangular dinner-table for at least two persons, and a second position in which the said board, turned by or rotated in a horizontal plane in an angle of 90°, is fitted between the two fixed panels, constituting a cross-shaped dinner table for at least four persons.

Furthermore, the above mentioned pivotable board is advantageously provided, at its underside, with two hinged flaps which are adapted to occupy two positions: a horizontal position in which they are folded under the board and superimposed to or on the aforesaid fixed panels, and a vertical position in which they lean upon the table frame, along the inner edges of the fixed panels, the said board being raised with respect to the said panels, the whole forming in this position an apartment bar.

Other features of the invention will appear in the following specification and in the accompanying drawings which represent, by way of example, an embodiment of the transformable table according to the invention.

Fig. 1 is a side elevation of the table in its first form, the pivotable board occupying its first position.

Fig. 2 is a plan view of the same.

Fig. 3 is a side elevation of the table in its second form.

Fig. 4 is a plan view of the latter.

Fig. 5 is a side elevation of the table set so as to form an apartment bar.

Fig. 6 is a perspective view of the table frame.

In the embodiment shown on the drawings, the frame of the table comprises a tubular frame formed by four uprights 1 connected at their lower ends to form a base by crossed braces 2 the ends of which are provided with rollers or casters 3. Higher up, the uprights are connected by parallel side or cross bars 4 which are, in turn,

2

connected intermediately by a cross brace 5. The uprights 1 are bent horizontally outwardly at 1a and connected two by two or in pairs at their outer ends, by an upper cross bar 1b, the parts 1a and 1b supporting, on each side of the table, a fixed panel 6.

A tray 7 provided with a surrounding rim may be placed upon the lower brace tubes 2, and a similar tray 8 may be provided higher up as on cross-bars or braces 4 and 5.

From the point of crossing of the lower braces 2 rises a central tube 9 which is maintained in position by the upper cross brace 5, and in which is slidably and rotatably mounted a shaft 10 supporting, by means of a cross-shaped member 10a, a rectangular board 11 which is adapted to cover the two fixed panels 6 and bridge the intermediate space or interval formed between these panels.

To the underside of this board 11 are hingedly connected at 12, 12, two flaps 13 which can be maintained flat against said board, by means of hooks 14 mounted in any convenient manner.

In its first position, the board 11, with the underlying flaps 13, covers the fixed panels 6 and is locked against rotation by the hooks 14 which are tilted downwards so as to engage the sides, side edges or ends of the fixed panels 6 (Fig. 1). Viewed from above, as shown on Fig. 2, the table has then the rectangular shape of the board 11 and may be used as a sideboard, or as a dinner-table for at least two persons placed at the transverse sides of the panels 6 and board 11.

In order to pass to the second position, the hooks 14 are lifted so as to hold the flaps 13 against the board 11, and the latter is turned 90° about the vertical shaft 10, so that it is able to fit between the panels 6 and be supported in the plane thereof, by resting on the inner portions of the horizontal parts 1a of the uprights 1 (Fig. 3). In this position, the table has, in plan view, the shape of a cross (Fig. 4) and may be used by four persons, in the same manner as would be a larger table with a square board the sides of which would be equal to the length of the board 11.

Finally, the board 11 being reset or raised above the panels 6, the hooks 14 may be disengaged so as to allow the flaps 13 to tilt downwardly, and to come to rest by or at their lower edges upon the inner portions of the parts 1a, preferably by means of notches 13a formed in the lower edges of the flaps 13. Angle pieces 15 secured to the bottom of board 11 spaced inwardly from and parallel to hinges 12, a distance substantially equal to the thickness of flaps 13 to brace and en-

sure the vertical position of the flaps 13, in which the lower edges of the latter are placed against the inner edges of the panels 6 (Fig. 5). The aforesaid notches lock the whole raised structure formed by the board 11 and the depending flaps 13 against rotation.

In this position, the board 11 is elevated, and the whole device forms a kind of apartment bar. The panels 6 form shelves for the glasses, while the bottles placed on the elevated board 11 are immediately at hand for the person attending to the bar. The ice bucket and other implements of the barman can also be placed conveniently.

Advantageously, the notches 13a in the edges of the flaps 13 will be large enough to make it easy to get hold of the board 11 in order to turn the same, when the flaps 13 are folded flat under the board as seen in Figure 1.

It will be understood that the invention is not limited to the embodiment which has been described and shown, and that it covers also any modifications made therein without departing from the scope of the appended claims.

I claim:

1. A transformable table comprising a frame, a vertical tube mounted centrally in said frame, a vertical shaft rotatably and slidably mounted in said vertical tube, a horizontal rectangular board mounted on the upper end of said vertical shaft, and two fixed horizontal panels mounted on said frame and on opposite sides of said vertical tube for selectively supporting said board, said panels being spaced the width of said rectangular board for selectively receiving said board therebetween, said board may rest upon said panels or be turned through an angle of 90° on said vertical shaft and lowered, with said vertical shaft sliding in said

vertical tube, to fit between said panels in the same horizontal plane.

2. A transformable table comprising a frame, a vertical tube mounted centrally in said frame, a vertical shaft rotatably and slidably mounted in said vertical tube, a horizontal rectangular board mounted on the upper end of said vertical shaft, two fixed horizontal panels mounted on said frame, and on opposite sides of said vertical tube for selectively supporting said board, said panels being spaced the width of said rectangular board for selectively receiving said board therebetween and two flaps hinged to the underside of said board and to be folded flat against the underside of said board so as to rest with said board on said panels, and when said board is raised to an elevated position with said vertical shaft sliding in said vertical tube, said flaps to be tilted to a vertical position in which they rest by their lower edges upon said frame and support said board in its elevated position.

PAUL FRANÇOIS GALLERET.
